UNITED STATES PATENT OFFICE

WARREN L. SULLIVAN, OF ROCHESTER, NEW YORK, ASSIGNOR TO PARAGON REVOLUTE CORPORATION, OF ROCHESTER, NEW YORK, A CORPORATION, OF NEW YORK

PRINTING MACHINE FOR SENSITIZED MATERIAL

Application filed November 20, 1930. Serial No. 496,960.

The present invention relates to printing machines for sensitized material and an object thereof is to provide means readily under control of an operative to vary the pressure of the holding belt on the light transmitting member. Another object of the invention is to provide for conditioning the sensitized material and material to be copied before presenting them to the light transmitting member so as to prevent the expansion of such materials when they come into contact with such surface.

To these and other ends, the invention consists of certain parts and combinations of parts, all of which will be hereinafter described: the novel features being pointed out in the appended claims.

In the drawings:

Fig. 1 is a vertical section through a printing machine constructed in accordance with this invention;

Fig. 2 is a front view of the same machine with parts broken away and the table and associated parts being omitted in order to show the belts or bands and the tensioning roller; and

Fig. 3 is a detail view of the driving mechanism taken substantially on the line 3—3 of Fig. 2.

In the illustrated embodiment of the invention, the frame of the machine embodies two end frames 1 suitably connected and supporting a rotary bed or cylinder 2 of light transmitting material such as glass. Within this bed is arranged an illuminating means or light source 3 in the form of an axial line of arc lamps.

A feeding means is employed for holding the sensitized sheet and material to be copied against the light transmitting bed. In this instance, this feeding means comprises a plurality of parallel belts or bands 4, each of which passes from a roller 5 upwardly and rearwardly behind the rotary bed 2 thence forwardly and over the top of the bed and downwardly in front of the bed to a roller 6. After passing under the roller 6, each belt passes upwardly and on the outer side of a roller 7, thence upwardly in front of and over a roller 8 rearwardly to a roller 9, thence

downwardly around the roller 9 behind a roller 10 to and under a roller 11. From the latter each belt or band passes under a roller 12 and thence upwardly over a roller 13 and downwardly to the under side of the roller 5. The driving of this feeding means may be effected in any suitable manner, but it is preferred to connect power to the shaft of the roller 5 so that through the belts or bands the sensitized material and the material to be copied are carried upwardly on those portions of the belts leading upwardly from the roller 5 into the intake and discharge throat 14 until such material passes into engagement with the rotary cylinder which is being turned by the bands. The materials then travel about the source of light until they are discharged through the throat 14 at the under side of the roller 6.

The belts, in this instance, are driven by the roller 5 which has a chain drive connection 35 with a shaft 37 on which a worm wheel 38 is arranged. This worm wheel meshes with a worm 39 on a shaft 40 carrying a disk 41. The latter engages an axially movable disk 42 which engages a driving disk 43 driven by a motor 60 through an endless belt 61. Movement of the disk 42 axially gives any desired speed in the feeding belts. The disk 42 is mounted to turn on a shiftable frame 44 which, by a link 45, connects with an arm on a rocking gear segment 46 meshing with a sliding rack 47 which also meshes with a gear on a shaft 48. The latter carries a hand wheel 49 which, when turned, changes the speed of travel of the belts.

The sheet of sensitized material, in this instance, passes around the edge of and then upward in front of a light shield 15 which covers the belts or bands 4 above the throat 14 to prevent the sensitized material being affected by the light source. The copied material is discharged into the tray or receptacle 19 which projects at its rear edge into the throat 14 beneath the roller 6.

The material may be held against the upwardly extending portions of the belts at the bottom of the throat 14 by feeding belts 16 which travel about a roller 17 geared to the roller 5 at one end of the machine so that the

belts 16 have the same surface speed as the belts 4. The belts 16 travel above and below a rigidly supported plate 18 and also around the upper edge of the plate. The sheet material may be fed from a roll 20 supported beneath a feeding table 21 which projects forwardly from the machine below the throat 14.

One of the features of this invention is the manner in which tension is placed upon or taken off the belts to cause them to exert more or less pressure on the cylindrical bed. This tensioning means comprises a movable supporting means for one of the rollers in this instance 12. This supporting means, in this instance, comprises two levers 22 on which the roll 12 is journaled, said levers being pivoted at 23 to the frame and having pivoted at 24 to their rear ends links 25, the lower ends of which are pivoted at 27 to the forward ends of arms 28 which extend forwardly from a rock shaft 29 to which a treadle 30 is secured. Downward pressure on the treadle serves to relieve the normal tension on the belts 4 produced by the weight of the roller 12.

Another feature of the invention is the conditioning of the sensitized material and the material to be copied (tracings, negatives and the like) so that the time these papers reach the illuminated bed they will have a temperature approximating that of the bed so that no expansion of said material will take place during the process of printing and thereby clearer printed lines will be obtained. In this instance, a heater preferably in the form of an electric resistance plate 31 is arranged beneath those portions of the belts passing upwardly and rearwardly from the roller 5 or below the bottom of the throat 14 so that the sheets after they are picked up by the feeding belts and before contacting with the illuminated bed are heated substantially to the temperature of the bed.

From the foregoing it will be seen that the sensitized sheet passes over the table 21 from the roller 20 onto the rearwardly and upwardly extending belt portion forming the bottom of the throat 14. The material to be copied is laid on the sensitized sheet while the latter lies over the table so that the sensitized sheet and material to be copied both pass beneath the feeding belts 16 and over the heater or conditioner 32, to the rotary illuminated bed 2 and is carried about the latter until the roller 6 is reached when the sensitized sheet passes upwardly and thence rearwardly to the developing machine, while the copied material is deposited in the tray 19.

What I claim as my invention and desire to secure by Letters Patent is:

1. In a machine for printing sensitized material, the combination with a light transmitting bed, and a light source illuminating

the same, of mechanism for causing the sensitized material and the material to be copied to travel past the light source in contact with the bed comprising a plurality of endless belts having parallel portions engaging said bed, a roller about which all of said belts pass, and means movably supporting said roller to permit the pressure of the belts on the light transmitting bed to be varied, said means including a pair of levers extending rearwardly from the said roller and having the same journaled between their front ends, said levers being fulcrumed intermediate of their ends, links pivoted to and extending downwardly from the rear ends of the levers, a rock shaft located at the back of the machine and having forwardly extending arms pivotally connected to the lower ends of the said links, and means for partially rotating the rock shaft to swing the said levers and lift the said roll.

2. In a machine for printing sensitized material, the combination with a rotatably mounted light transmitting bed, and a source of illumination therefor, of a plurality of belts having parallel portions contacting with said rotary bed, a roller about which all of said belts pass, and means for supporting said roller for movement to vary the pressure of the belts on the rotary bed, said means including a pair of levers extending rearwardly from the said roller and fulcrumed intermediate of their ends and having the said roller journaled between their front ends, links connected to and extending downwardly from the rear ends of the said levers, a rock shaft located at the back of the machine and having forwardly extending arms connected to the lower ends of the said links, and a treadle located beneath and extending from the back to the front of the machine and connected at its rear end to the said rock shaft, said treadle being adapted to be depressed to partially rotate the rock shaft and swing the said levers to lift the said roll.

3. In a machine for printing sensitized material, the combination with a light transmitting bed, and a source of illumination, of mechanism for effecting the movement of sensitized material and material to be copied to and past the light source in contact with said bed, and means for conditioning the sensitized material and the material to be copied while such material is on the moving mechanism and before such material has come in contact with the bed.

4. In a machine for printing sensitized material, the combination with a light transmitting bed, and means for illuminating said bed, of a plurality of belt laps leading upwardly and rearwardly from a point below the bed and behind the bed in contact with such bed, and a heater arranged beneath such laps to heat material before the latter is carried into contact with the illuminated bed.

5. In a machine for printing sensitized material, the combination with a rotary light transmitting bed, and means for illuminating the same, of a feeding table projecting forward below the bed, and mechanism for moving material from the feeding table rearwardly and upwardly beneath the bed, and thence into contact with the bed, said mechanism embodying a plurality of parallel belt 10 laps extending rearwardly and upwardly from the table into contact with the bed, and means for conditioning the material as it passes rearwardly and upwardly from the table and before it contacts with the bed, said 15 conditioning means being arranged beneath the rearwardly and upwardly extending belt laps.
